(57) **CLAIM**

The ornamental design for a combined metal food container and lid, as shown and described.

DESCRIPTION

FIG. 1 is a front perspective view of a combined metal food container and lid;

FIG. 2 is a front elevation view thereof, the rear elevation view being substantially the same as the front elevation view except that the tab would be on the opposite side;

FIG. 3 is a right elevation view thereof, the left elevation view being substantially the same as the right elevation view;

FIG. 4 is a top plan view thereof;

FIG. 5 is a bottom plan view thereof;

FIG. 6 is a sectional view of the combined metal food container and lid taken along line 6-6 of FIG. 4;

FIG. 7 is a front perspective view of a combined metal food container and lid according to another embodiment;

FIG. 8 is a front elevation view of the combined metal food container and lid of FIG. 7, the rear elevation view being substantially the same as the front elevation view except that the tab would be on the opposite side;

FIG. 9 is a right elevation view of the combined metal food container and lid of FIG. 7, the left elevation view being substantially the same as the right elevation view;

FIG. 10 is a top plan view of the combined metal food container and lid of FIG. 7;

FIG. 11 is a bottom plan view of the combined metal food container and lid of FIG. 7; and,

FIG. 12 is a sectional view of the combined metal food container and lid taken along line 12-12 of FIG. 10.

(Continued)

The broken lines shown are included for the purpose of illustrating portions of the combined metal food container and lid that form no part of the claim.

1 Claim, 10 Drawing Sheets
